COVER STRUCTURE FOR SMOKING PIPES

David P. Lavietes, Brooklyn, N. Y.

Application May 13, 1937, Serial No. 142,330

4 Claims. (Cl. 131—176)

The invention relates to cover structures for smoking pipes, and more particularly to a cover structure for a pipe having a bowl cover permitting it to be used without likelihood of the escape of sparks and ashes when driving an automobile or in the out-of-doors.

Pipes having covered bowls have been extensively used for many years. In one form of such pipe, the top of the bowl is fitted with a ferrule having a cover provided with draft openings hinged thereto. Other forms of such pipes have had fittings removably connected with the top of the bowl by means of spring tongues fitting within the bowl, or spring clips, portions of which fit within the bowl and other portions of which are sprung over the edge of the bowl so as to co-operate with the portion of the clip within the bowl in a manner to clamp the cover upon the bowl. In still another type of covered pipe, the top of the bowl is provided with exterior screw threads, and a flanged cover having interior screw threads co-operating with the screw threads about the bowl, is used.

When smoking a pipe, ready access must be had to the bowl for the purpose, not only of charging the pipe with tobacco, but to permit ashes to be knocked from the bowl, the heel to be removed therefrom, or the cake in the bowl to be reduced by means of an ordinary pipe

reamer.

The presence of a cover structure permanently connected with the bowl interferes with the various practices above referred to, which are incidental to the use of a pipe.

It is not desirable to have metal parts within the bowl of a pipe, since such metal parts are subjected to high temperatures and, particularly with a new pipe having a briar wood bowl, prevent the caking of the bowl which a pipe smoker considers to be essential to a cool smoke. It also prevents a satisfactory coloring of the bowl as a result of the use of the pipe.

The use of spring tongues clamping the cover upon the bowl is objectionable, because in re-moving and mounting the cover from or upon the bowl, the exterior spring tongues mar the finish of the bowl of the pipe, and the clamp jaws within the pipe become highly heated and prevent caking in the manner immediately above referred to.

For free access to the bowl, either for charging or shaking out the ashes, a hinged cover only is required, but when removing the heel or when reaming the bowl, complete removal of the cover from the bowl is desirable. It is also

desirable that the cover be capable of being removed from the bowl so that while indoors, the pipe may be smoked in the usual way and will have the appearance of an ordinary pipe.

With the above conditions in mind, I have provided a cover structure for a pipe having a cover resting upon the top of the bowl and secured thereto by a hinge plate removably attached to the exterior of the bowl at a predetermined point thereof by inconspicuous means permanently connected with the bowl. In this manner, the cover may be raised and lowered at will by moving the cover about its hinge to an extent to expose the top of the bowl to permit charging of the bowl or removal of the ashes therefrom. If it be desired to use the pipe without the cover, or to remove the heel or ream the cake from the bowl, the hinge plate may be quickly disconnected from the bowl with a short right line movement of the hinge plate so limited as to practically eliminate likelihood of marring of the exterior of the bowl.

The manner of attaching the hinge plate to the bowl is such as to firmly hold the hinge plate in position while the pipe is being used with the cover in place, while permitting the quick disconnection of the plate from the bowl when the removal of the cover is desired.

No portion of the cover structure comes in contact with the burning tobacco, and by mounting the cover in the manner to be hereinafter described, overheating of the metal of the cover will not occur, so that the cover may be opened and closed or entirely removed from the pipe without personal discomfort.

Furthermore, the construction of the hinge plate and the manner of securing it to the outside of the bowl permits the instant disconnection of this plate from the bowl, and the removal of the cover from the pipe with little effort and with the use of one hand only, notwithstanding that the construction of said hinge plate is such that while the pipe is in use, the hinge plate is so firmly held against the bowl as to preclude accidental displacement of the cover.

The invention consists primarily in a cover structure for a smoking pipe, having means exposed exteriorly of the bowl thereof, said structure embodying therein a cover plate having draft openings therethrough, a hinge plate shaped to conform to the outer surface of the bowl of a pipe adjacent the top thereof and having a resilient portion having its upper edge free normally sprung outwardly of the bowl, and a hinge connection between said hinge plate and said

cover plate, said resilient portion being adapted to be detachably engaged with said exposed means, whereby said plate may be forced and held in intimate contact with the bowl of the pipe by the tension of said resilient portion; and in such other novel features of construction and combination of parts as are hereinafter set forth and described, and more particularly pointed out in the claims hereto appended.

10 Referring to the drawing,

Fig. 1 is a condensed side view of a pipe embodying the invention upon an enlarged scale with the upper portion of the bowl and the cover structure shown in section;

15 Fig. 2 is an elevation from the right of Fig. 1;

Fig. 3 is a view of the cover structure removed from the pipe with the cover plate raised; and

Fig. 4 is a section on the line 4—4 of Fig. 3.

Like numerals refer to like parts throughout 20 the several views.

In the embodiment of the invention shown in the drawing, the bowl 10 of the pipe is of cylindrical form with a slight taper toward the top thereof, the shank of the pipe being shown 25 at 11 and the bit at 12. Pipes are made with many different sizes and designs of bowls and bits, and the cover must be so proportioned as to adapt it for use with each particular size and design of pipe.

30 This cover mechanism consists of a cover plate 13 resting upon the top of the bowl of the pipe. The central portion of the plate 13 is bulged upwardly at 14 and provided with draft openings.

Co-operating with the cover plate 13 is a hinge 35 plate 15, this hinge plate being shaped so as to conform to the curvature of the outer surface of the bowl of the pipe with which the cover structure is to be used. With this construction, side tilting of the plate by reason of the curvature of the bowl and of the plate is prevented.

40 The cover plate 13 is connected with the hinge plate 15 by means of an ordinary hinge 16, the sockets of which are located above the plane of the edge of the cover plate 13. By using a tight hinge between the cover plate and the hinge plate, sufficient resistance is offered to the turning of the cover plate to hold this plate in the position shown in Fig. 3, when removing ashes from the pipe or charging tobacco thereinto. In other words, the cover plate may be turned about its hinged connection with the hinge plate to any extent up to 180° or more and have the cover plate remain in any position when the turning movement is arrested.

50 The cover plate is provided with a short tongue 17 projecting beyond the top of the bowl to facilitate the opening of the cover.

55 While the shape of the hinge plate conforms with the exterior of the bowl adjacent the top 60 thereof and prevents turning of the plate about an axis at right angles to the axis of the bowl, it is essential, when securing the cover upon the pipe, that this plate be held firmly against the bowl, since any looseness of the plate will permit 65 a slight tilting action thereof, resulting in the marring of the surface finish of the bowl as a result of the scraping of the metal of the hinge plate across this surface. This will occur even though the amount of the movement of the plate 70 be small.

75 Because of this necessity, I provide the hinge plate with a resilient portion which, in the form of the invention shown, consists of a spring tongue 18, the tension of which is such as to normally force the hinge plate toward the bowl

as the result of the engagement of this resilient portion or spring tongue with a co-operating abutment carried by the bowl of the pipe. The spring tongue 18 is integrally formed with the plate 15 and projects toward the hinge connection 16 between the plate and the top cover and outwardly of the bowl.

80 The use of a spring tongue as shown has been found to be highly desirable in securing the maximum pressure of the plate against the bowl 10 toward the top of the former, and as also permitting the tensioning of the resilient portion or spring tongue with a gradually increasing pressure by a movement of the plate downwardly of the bowl. In this manner, the attachment of 15 the spring plate 15 and its detachment from the bowl is a very simple operation, and is accomplished by a right line movement of the hinge plate along the bowl, thus avoiding any such tilting of the plate as might bring the edge of 20 the plate in contact with the bowl and cause possible scratching of the surface of the latter.

25 In the form of the invention shown, the hinge plate is secured to the bowl by means of a headed stud 19 carried by the bowl, the head of the stud 25 being spaced from the surface of the bowl a distance substantially equaling the thickness of the metal stock in the hinge plate 15. The use of a resilient tongue permits thin sheet metal to be used for the hinge plate, and the resiliency 30 inherent to the tongue ensures a tight fit between the plate and the outer surface of the bowl, notwithstanding irregularities in said surface, in the spacing of the head of the stud 19 from the bowl or in the hinge plate itself.

35 The tongue 18 is provided with a keyhole slot 20, the enlargement of which is adjacent the end of the tongue connected with the plate 15. The tongue, adjacent the reduced portion of the slot, may or may not have a close sliding fit between 40 the stud and the bowl. So long as the plate 15 is in close contact with the surface of the bowl, movement of the hinge plate, except in a direction parallel with the axis of the bowl or toward and from the stem, is prevented by the close fitting of the hinge plate and the bowl.

45 By using a resilient portion of the spring plate for securing a close fit between same and the bowl, accidental displacement of the cover is prevented, and yet the hinge plate may have a 50 free sliding movement in relation to the stud 19 in placing the cover upon or removing it from the bowl.

55 In mounting the cover upon the bowl, it is merely necessary to pass the enlarged portion 55 of the keyhole opening 20 over the stud. At this point, the tongue 18 is substantially in the same plane as the rest of the hinge plate. The hinge plate 15 is then forced downwardly with a sliding movement along the surface of the bowl, and as the portion of the tongue 18 having the reduced portion of the keyhole opening passes along the bowl, the spring tongue is forced downwardly within the opening in the hinge plate. The spring thus tensioned will force the whole hinge plate toward the bowl of the pipe as a result of the tendency of the tongue to have a reflex action, and while there may be slight clearance between the tongue and the surface of the bowl because the head of the stud 19 is 60 spaced from the bowl a distance slightly greater than the thickness of the metal stock in the hinge plate, this is immaterial since all other portions of the plate will be spring pressed into 65 contact with the bowl.

The spring tongue 18 has the same curvature as the hinge plate 15, while the stud has an angular shoulder presented towards the bowl of the pipe. Consequently, the portion of the head 5 of the stud overhanging the tongue at opposite sides of the slot will, when applying the cover to the bowl, readily engage the head of the stud, thus permitting a fairly close fit between the head of the stud and the bowl of the pipe. The degree 10 of pressure exerted by the tongue may be varied by changing the angle of projection of the tongue in relation to the normal plane of the hinge plate. The head of the stud 19 is spaced from the nearest portion of the bowl only a few thousandths 15 of an inch, possibly from .010 to .015, and the head may be rounded to avoid exposed abrupt edges.

When the cover has been attached in the manner described, a pipe with the cover thereon 20 may be carried in the pocket and handled in the usual manner with little or no likelihood of the accidental escape of the hinge plate from the stud. The cover may be turned to open and close the bowl as desired, and this movement will 25 have no tendency to displace the hinge plate 15. To remove the cover it is merely necessary to raise it and pull it away from the top of the bowl. This movement will cause the hinge plate to slide 30 along the bowl without scratching same until the head of the stud is positioned within the enlarged portion of the keyhole slot 20, whereupon the hinge plate may be moved from the bowl, the stud remaining in position thereon.

The small size of the head of the stud and its 35 position in relation to the bowl will not be objectionable if it be desired to smoke the pipe without the cover thereon. In fact, studs having heads of distinctive forms may be used as a trade indicia of the origin of the pipe.

40 It is essential that the resilient portion of the tongue 18 of the hinge plate shall project outwardly of the bowl to get the desired spring action in fitting the hinge plate to the bowl.

The cover plate 13 and the hinge plate 15 are 45 preferably made of German silver or other metal stock plated with a metal which will not readily tarnish when subjected to heat. As a matter of fact, the bowl of the pipe protects the hinge plate from the effects of the heat, and the draft down- 50 wardly of the bowl through the draft openings in the central portion 14 of the cover plate will protect the outer finish of said plate, although the inner surface thereof may be smutted by the smoke and ashes from within the bowl.

55 It is not my intention to limit the invention to the precise details of construction shown in the drawing, it being apparent that such may be varied without departing from the spirit and scope of the invention.

60 Having described the invention, what I claim as new and desire to have protected by Letters Patent, is:

1. A cover structure for a smoking pipe having means exposed exteriorly of the bowl thereof, 65 said structure embodying therein a cover plate having draft openings therethrough, a hinge plate shaped to conform to the outer surface of the bowl of a pipe adjacent the top thereof and having a resilient portion having its upper edge 70 free normally sprung outwardly of the bowl, and

a hinge connection between said hinge plate and said cover plate, said resilient portion being adapted to be detachably engaged with said exposed means, whereby said plate may be forced and held in intimate contact with the bowl of 5 the pipe by the tension of said resilient portion.

2. A cover structure for a smoking pipe having means exposed exteriorly of the bowl thereof, 10 said structure embodying therein a cover plate having draft openings therethrough, a hinge plate shaped to conform to the outer surface of the bowl of a pipe adjacent the top thereof, a hinge connection between said hinge plate and said cover plate, and a spring tongue carried by 15 said hinge plate with its free end positioned adjacent said hinge connection and normally sprung outwardly of the bowl, said spring tongue being adapted to be detachably engaged with said exposed means, whereby said plate may be forced and held in intimate contact with the bowl 20 of the pipe by the tension of said spring tongue.

3. A cover structure for a smoking pipe having a headed stud exposed exteriorly of, and with its head spaced from, the bowl thereof, said structure embodying therein a cover plate having draft openings therethrough, a hinge plate shaped to conform to the outer surface of the bowl of a pipe adjacent the top thereof, a hinge connection 25 between said hinge plate and said cover plate, and a spring tongue carried by said hinge plate with 30 its free end positioned adjacent said hinge connection, said tongue being normally sprung outwardly of the bowl, and having a keyhole slot therein with its enlarged portion remote from the free end of the tongue, said spring tongue, 35 adjacent the narrow portion of said keyhole slot, being adapted to co-operate with the head of said stud, whereby said plate may be forced and held in intimate contact with the bowl of the pipe by the tension of said spring tongue. 40

4. A cover structure for a smoking pipe having a stud adjacent the top and exteriorly of the bowl thereof, said stud having an enlarged head, the face of which presented toward the bowl is parallel with a plane tangential thereto and 45 spaced therefrom, said structure embodying therein a cover plate having draft openings therethrough and a short tongue adapted to project beyond the edge of the bowl to facilitate the opening of the cover, a hinge plate shaped to 50 conform to the outer surface of the bowl of a pipe adjacent the top thereof, a hinge connection between said hinge plate and said cover plate, and a spring tongue of a thickness less than the 55 distance between the head of said stud and the bowl of the pipe, said tongue being formed integrally with said hinge plate with its free end positioned adjacent said hinge connection, being normally sprung outwardly of the bowl and having a keyhole slot therein with its enlarged portion 60 remote from the free end of the tongue, said spring tongue, adjacent the narrow portion of said keyhole slot, being adapted to co-operate with the head of said stud, whereby engagement of said spring tongue with said head will force 65 and hold said hinge plate in intimate contact with the bowl of a pipe by the tension of said spring tongue.

DAVID P. LAVIETES.
